ATTORNEY.

UNITED STATES PATENT OFFICE.

HENRY P. HURT, OF MEMPHIS, TENNESSEE, ASSIGNOR TO W. W. DEUPREE, OF MEMPHIS, TENNESSEE.

DESIGN FOR A FINGER-RING, BAR-PIN, OR SIMILAR ARTICLE.

56,972.

Specification for Design.

Patented Jan. 25, 1921.

Application filed May 1, 1918. Serial No. 231,962. Term of patent 7 years.

To all whom it may concern:

Be it known that I, HENRY P. HURT, a citizen of the United States of America, residing at the city of Memphis, State of Tennessee, have invented a new, original, and ornamental Design for Finger-Rings, Bar-Pins, and Similar Articles, of which the following is a specification, reference being had to the accompanying drawing, forming a part thereof.

The figure illustrates my new design applied to a finger ring.

I claim:

The ornamental design for a finger ring, bar pin, or similar article as shown.

HENRY P. HURT.
